LUBRICANT PUMP

Ernest W. Davis, River Forest, Ill.

Application November 30, 1945, Serial No. 631,980

2 Claims. (Cl. 103—166.5)

1

This invention relates to pumps, and particularly to the type employed for dispensing lubricant including heavy oil or grease from a container in a manner which insures delivery of the lubricant at a considerable pressure enabling it to force its way into bearings against appreciable resistance.

One object of the invention is to provide a new and improved lubricant pump of relatively simple construction and of high efficiency.

Another object of the invention is to provide a lubricant pump in which the outlet is controlled by a valve normally closed by means of a spring and opened by the pressure developed in the pump, but in such a manner that the outlet pressure at which the lubricant is delivered is not reduced by the force of the spring.

It is also an object of the invention to provide a lubricant pump in which the outlet is controlled by a piston valve normally closed by a spring with sufficient force to shear off from the edge of the outlet port any material adherent thereto.

A further object of the invention is to provide a new and improved lubricant pump in which the outlet through which the lubricant is expelled by the force of the plunger stroke is a lateral opening controlled by a slide valve actuated by pressure developed in the pumping action but in such a manner that the lubricant is delivered at the full pressure attained in the pump cylinder.

Other objects and advantages of the invention will appear from the following description taken in connection with the drawings, in which the single figure is a vertical axial view of a lubricant pump embodying this invention, together with conventionally represented driving means and lubricant delivery means therefor.

Lubricant pumps of the type to which this invention relates are designed to extract and deliver lubricant usually from a shipping container, such as a drum, into which the pump itself is preferably inserted and supported near the bottom of the container. As shown in the figure, the bottom of the container is represented in section at 10 and pump cylinder 12 is shown with a terminal fitting 14 at its lower end which serves to close the end of the cylinder 12 and also provides a valve chamber and an outlet passage through which lubricant is delivered. A plunger 16 is arranged to be reciprocated in the cylinder 12 by a pump rod 17 connected to any suitable means such as a compressed air motor including a cylinder 18 carried by a support 20 which is disposed over the container. The upper part of the container is indicated at 11.

2

The pump cylinder 12 is reduced and provided with threads 22 at its upper end for connection with a supporting tube 24 by which the pump is suspended from the support 20 and preferably a downwardly open bell 26 is secured between the lower end of the tube 24 and the shoulder 28 on the cylinder and extends downwardly therefrom to within a short distance above the bottom wall 10 of the container. The cylinder 12 is provided with one or more inlet ports 30 near its upper end through which lubricant is drawn into the cylinder 12 by suction produced by the upward stroke of the plunger 16, and the purpose of the bell 26 is to require that the lubricant in the container 15 shall enter the ports 30 by flowing around the lower edge of the bell 26 so that as the level of lubricant in the container falls, the lubricant will continue to be available after the level has dropped below the level of the ports 30.

20 The fitting 14 includes a passage 32 with an outlet pipe 34 connected thereto and leading upwardly through the support 20 to a boss 36 to which there is preferably connected a flexible hose 38 and a delivery nozzle 40 of conventional form. The outlet passage 32 extends from a port 42 disposed laterally in the valve chamber 44 which is in effect an extension of the cylinder 12, and the port 42 is controlled by a piston valve 46 slidably axially in the cylindrical valve chamber 30 44 for opening or closing the port 42. The valve 46 is seated upon a relatively stiff spring 48 pocketed in the valve chamber 44 between the valve member and the lower end of the chamber which forms the closed end of the pump cylinder 35 and said valve is provided with a reduced guide stem 50 slidably in a bore 52 formed in the lower end of the fitting 14. At the upper end of the bore 52 a shoulder 54 serves as a stop to engage a shoulder 56 on the valve stem for limiting the opening movement of the valve. The valve body 46 is formed with an axially disposed passage 58 and lateral ducts 60 connected therewith providing communication between the interior of the cylinder 12 and the space in the valve chamber 44 below the valve 46. It may be understood that the valve 46 is forced open by the pressure developed by the downward stroke of the plunger in the cylinder 12 and that by reason of the passages 58 and 60 extending through the valve, the effective area on which the pressure operates is the cross-section of the lower portion of the stem 50.

With this arrangement, the inlet ports 30 remain closed by the plunger 16 until it has nearly reached the upper limit of its stroke. This produces a strong partial vacuum in the cylinder

12 so that as the plunger uncovers the ports 30 there is powerful suction exerted upon the grease outside the cylinder and a substantial charge of grease is drawn into it. Then as the plunger descends and closes the ports 30 it builds up pressure in the cylinder 12 but does not at first expel any grease therefrom. The provision of a relatively stiff spring 48 holds the outlet valve 46 closed until the pressure is sufficiently high in the cylinder to overcome the force of the spring and move the valve 46 downwardly to a position uncovering the outlet port 42. The charge of grease is then driven through the passage 32 and pipe 34 for delivery by way of the nozzle 40. As the plunger 16 reverses its motion and travels upwardly in the cylinder 12, the reduction of pressure permits the spring 48 to close the valve 46 in the initial portion of the upward stroke and thereafter the plunger operates to create a partial vacuum in the cylinder 12 as already noted.

It will be seen that although the pressure developed in the cylinder 12 serves to compress the spring 48 in opening the valve 46, this same unit pressure is delivered through the outlet 42 for expelling the grease through the nozzle 40; it is not diminished but is merely measured and regulated by the pressure of the spring 48.

The pump can readily be made double-acting by making the pump rod 17 smaller than the plunger 16 or by inserting at the connection between the plunger and the pump rod a disc or flange of approximately the same diameter as the interior of the casing 24, and then connecting the pipe 34 into the casing 24 and connecting the upper end of this casing with the discharge passage in the boss 36.

While there are shown and described herein but a single embodiment of the invention, it is to be understood that the invention is not limited thereto or thereby but may assume numerous other forms and includes all modifications, variations and equivalents coming within the scope of the appended claims.

I claim:

1. In a lubricant pump a cylinder closed at one end, the closed end having a bore of substantially smaller diameter than that of the cylinder, a plunger reciprocable through the opposite end of said cylinder to perform a suction stroke away from said closed end and a pressure stroke toward said end of the cylinder, said cylinder

5 having an inlet port remote from its closed end, said port being uncovered by the plunger to admit lubricant to the cylinder during completion of the suction stroke and being closed by the plunger in the initial portion of the pressure stroke, said cylinder having an outlet passage leading from a port disposed laterally in the cylinder near its closed end, valve means controlling said port comprising a piston slidable 10 in the cylinder over said port, and a spring seated in the closed end of the cylinder and reacting against said piston valve to hold it normally in position to cover said port, the valve having a portion extending through the bore at the closed 15 end of the cylinder, said valve also having a passage through it leading to the space in which said spring is located.

2. An outlet valve for a pump cylinder comprising, a body having axially aligned communicating bores of different diameters extending through it, means for securing the body to the discharge end of a pump cylinder in communication with the large bore of the body, an outlet port extending laterally from the large bore, 20 a piston valve slidable in the large bore and having a portion located at all times in the smaller bore and closing the latter, said valve having a port providing communication at all times between the outer end of the large bore and the space between the valve and the smaller bore, and a spring exerting a force on the valve to move it toward the open end of the large bore and normally holding it in position closing the outlet port.

ERNEST W. DAVIS.
